UNITED STATES PATENT OFFICE

MILLER REESE HUTCHISON, OF LLEWELYN PARK, WEST ORANGE, NEW JERSEY, AS
SIGNOR TO PREMIER LABORATORY COMPANY, A CORPORATION OF DELAWARE

SOUND-PROPAGATING DIAPHRAGM

Application filed May 2, 1928. Serial No. 274,528.

The invention relates to sound propagating diaphragms.

One object of the invention is to provide an article of the character described by which 5 sounds of both the upper and lower portions of the musical register may be simultaneously produced without alterations or adjustment of the device.

A further object of the invention is to provide a sound propagating diaphragm one portion of which will vibrate to produce sound waves of the upper portion of the musical register while another portion of the diaphragm vibrates to produce sound waves of 15 the lower portion of the musical register.

One feature of the invention relates to the provision of connecting means between two portions of a sound propagating diaphragm whereby vibrations of one portion of the diaphragm will produce vibration of a different characteristic in the other portion of the diaphragm.

Another feature of the invention relates to the provision of a connecting means between 25 portions of a sound propagating diaphragm whereby sound waves of unlike characteristics propagated simultaneously from the different portions of the sound propagating diaphragm will not cause interference with their vibrations.

Other objects and features will appear from the following description in connection with the accompanying drawings in which

Figure 1 is a side elevation of the present 35 invention with a portion broken away.

Figure 2 is a front elevation of the sound propagating diaphragm embodying the present invention.

Like reference characters denote like parts 40 in the several figures of the drawing.

In the following description and claim, parts characteristic features and functions will be identified by specific means for convenience of expression, but they are intended 45 to be as generic in their application to similar

parts or equivalent construction as the art will permit.

Referring to the drawings for supporting a sound propagating diaphragm a base 10 is provided to which is securely attached a supporting rim 11 supporting a sound propagating diaphragm. An electromagnetic unit 12 is provided, for actuating the diaphragm, supported by a cross member 13 secured to the rim 11. The electromagnetic unit 12 includes an actuating arm 14 one end of which is secured to the sound propagating diaphragm for actuating the diaphragm in response to electrical waves imparted to the electromagnetic unit 12.

For controlling the electromagnetic unit 12 in accordance with a signal wave, there is provided an energy responsive device 20, shown in the form of an antenna positioned to intercept radiant energy or so-called Hertzian waves. It is understood that such waves may be emitted from a radio broadcast station of conventional type, but as the emission of such energy forms no part of the present invention, it is thought that a detailed description thereof may be omitted herein. The emitted energy preferably takes the form of a carrier wave of high frequency modulated in accordance with a signal current, the signal current corresponding in wave form to 75 sound waves. The antenna 20 at the receiving station is operatively connected to a tuner 21, a ground or counterpoise 22 being provided therefor. The tuner 21 may be variably adjusted so as to tune the circuits 20, 22 to 80 the frequency of the carrier wave which it is desired to receive and a connection comprising a pair of wires 23—23 extends from the tuner 21 to a detector 24 for impressing thereon electrical waves of this predetermined frequency. The detector 24 may be of any usual form for detecting high frequency energy and producing therefrom rectified or detected waves of signal frequency. These signal waves are transmitted over a pair of conduc-

tors 25 extending to the input of an amplifier 26 whereby the signal energy is amplified to a desired degree. A pair of conductors 27 forms an operative connection from the output of the amplifier 26 to the electromagnetic unit 12. Thus undulatory current of signal frequency is impressed upon the electromagnetic unit 12 under control of received radiant energy.

- 10 For producing sound waves of both upper and lower portions of the musical register, a sound propagating diaphragm 30 is provided comprising a cone formed from fibrous material such as paper or the like, supported 15 by the supporting rim 11, its apex being operatively connected to the actuating arm 14. A plurality of apertures 31 are provided dividing the cone 30 into a central cone 32 and a surrounding truncated cone 33. The apertures 31 are preferably arranged closely adjacent forming a circle of apertures of a radius approximately one fourth the radius of the cone, the distance of spacing being approximately equal to the diameter of the apertures. These apertures effect the damping 25 of the vibrations passing from the cone 32 to the truncated cone 33.

In the operation of the device waves of the desired frequency are selected detected and 30 amplified by the energy responsive device 20 and are supplied to the electromagnetic unit 12 which causes oscillation of the actuating rod 14 or if desired rod 14 may be oscillated by a stylus operating on a phonographic record. Oscillations of the actuating rod 14 are imparted to the cone 30 through the connecting of rod 14 to the apex of the cone 32, which because of its so small circumference and direct attachment to the actuating arm 14 35 will be caused to vibrate at high frequency producing sound waves of the upper portion of the musical register. Vibrations of the central cone 32 are imparted to the truncated cone 33 through the material between the apertures 31 in the face of the cone. Thus the vibration of the truncated cone 33 will be 40 similar to but of a lower frequency and of greater length than the vibration of the central cone 32, propagating sound waves of the 45 lower portion of the musical register.

50 Thus it may be seen that the invention provides a sound propagating cone or diaphragm which will be small in size and light in weight, easy to manufacture and which will be adapted for the simultaneous propagation of sound waves of both the upper and lower portions of the musical register.

The invention upon which this application 55 is based is broader than the specific embodiments shown and described for the purpose of illustrating at least some of the ways in which it may be employed. The scope of the invention is therefore to be understood as not 60 being limited by the present specific descrip-

tion. I intend no limitations other than those imposed by the claim.

What is claimed is—

70 A sound propagating diaphragm comprising a cone having a circular line of closely adjacent apertures symmetrically arranged, the center of curvature coinciding with the center of said cone, the radius of said circle being approximately one fourth the radius of the cone.

75 Signed at New York, in the county of New York and State of New York this 10 day of January, A. D. 1928.
